L. KAPLAN

RUBBER HEEL

Filed June 29, 1923

FIG. 1.

FIG. 2.

Inventor:
LOUIS KAPLAN

By *Monroe Miller*
Attorney.

Patented May 19, 1925.

1,538,332

UNITED STATES PATENT OFFICE.

LOUIS KAPLAN, OF NEW YORK, N. Y.

RUBBER HEEL.

Application filed June 29, 1923. Serial No. 648,484.

To all whom it may concern:

Be it known that I, LOUIS KAPLAN, a citizen of the United States, residing at New York city, in the county of New York and

5 State of New York, have invented certain new and useful Improvements in Rubber Heels, of which the following is a specification; reference being had therein to the accompanying drawing.

10 The present invention relates to rubber or cushion heels, and one object of the invention is the provision of such a heel having portions of different kinds of rubber or resilient material to increase the wearing 15 properties and resilience of the heel, and formed with grooves or portions whereby to equalize the wear and resilience between said portions.

Another object is the provision in the 20 heel, at the point where the greatest wear occurs, of an insert composed of metals or other materials having different degrees of hardness, whereby to effectively resist the wearing or running down of the heel.

25 With the foregoing and other objects in view, which will be apparent as the description proceeds, the invention resides in the construction and arrangement of parts, as hereinafter described and claimed, it being 30 understood that changes can be made within the scope of what is claimed, without departing from the spirit of the invention.

The invention is illustrated in the accompanying drawing, wherein—

35 Figure 1 is a bottom plan view of the improved heel.

Fig. 2 is a section on the line 2—2 of Fig. 1.

40 The heel or other tread member to be applied to a shoe or other article of footwear is composed of the halves or portions 7 and 8 at the opposite sides of and united along the longitudinal median line of the heel. The division line between the halves 45 or portions, however, may be at different positions, with said portions of different sizes. The portion 7 is composed of comparatively hard but resilient rubber while the portion 8 is composed of comparatively 50 soft rubber, although other resilient materials may be used, the term "rubber" being used with such broad meaning as to include equivalents.

The heel is attached to the shoe or article of footwear with the soft rubber portion 8 at the outer side of the foot and the

hard rubber portion 7 at the inner or arch side of the foot, whereby when standing with the heel flat on the surface, the portion 7 provides a firm although resilient 60 support. The portion 7 provides for an effective cushioning action in walking, such portion 8 coming into contact with the surface first, and receiving the greatest pressure of impact. Also, by using the two 65 different grades of rubber or other material, one comparatively soft and the other comparatively hard, the wearing properties of the heel are increased. Thus, on some surfaces the soft rubber portion 8 may tend 70 to wear away more quickly, whereas the harder rubber portion 7 will resist such wear, and on other surfaces the portion 7 may tend to wear away quicker while the portion 8 will resist such wear. In this 75 way, wearing down of the heel is not so fast as with a heel composed of the same kind of material, and the wear is also distributed between the two portions 7 and 8.

In some cases the heel is worn away 80 quicker at the inner or arch side, in which event the heel may be applied with the softer portion 8 at the inner or arch side of the foot.

In order to equalize, as much as possible, 85 the wear and resilience between the portions 7 and 8, the tread surface of the heel is provided with U-shaped grooves or channels 9 which have their terminals extending forwardly and terminating adjacent to the 90 forward end or breast of the heel, with one terminal of each groove ending in the portion 7 and the other terminal ending in the portion 8. Said grooves are arranged with their terminals disposed side by side 95 in the respective portions 7 and 8, with the intermediate portions of the grooves crossing or intersecting one another near but spaced from the rear end of the heel.

The ends 10 of the grooves 9 in the portion 8 are narrow and shallow, and are spaced apart further than the ends or terminals 11 in the portion 7, and said terminals 11 are comparatively wide and deep. The grooves 9 decrease gradually in width 100 and depth from the ends 11 to the ends 10, whereby the wearing qualities of the heel are gradually decreased from the ends 10 of the grooves 9 in the portion 8 to the ends 11 of the grooves in the portion 7, and, conversely, whereby the resilience afforded by the grooves decreases from the ends 11 to

the ends 10 of said grooves. The deeper and wider portions of the grooves will lend resilience to the portion 7, as well as enabling said portion to wear away quicker, it being noted that the portion 8 has broad tread surfaces between the grooves 9 while the portion 7 has narrow tread surfaces between said grooves. In this way, the grooves render the portion 7 more resilient, although the material of said portion is comparatively hard, and the grooves also have a tendency to equalize the wear between the hard and soft portions, so that the heel will have a tendency to wear down evenly or uniformly. The grooves may also assist in preventing slipping of the heel on wet or slippery surfaces, although same is secondary.

An insert 13 is provided in the heel at the point where the most wear occurs, and, as shown, the insert 13 is disposed in the rear end portion of the portion 8 in an oblique position. The insert 13 is composed of the outer half or piece 14 of suitable hard metal and the inner half or piece 15 of suitable soft metal, said pieces being welded or otherwise secured together. The insert 13 is thickened or widened, as at 16, between its ends, to offer greater resistance where subjected to the greatest wear. The hard portion or piece 14 of insert is disposed outermost or nearest to the margin of the heel to receive the brunt of the burden in resisting wear.

By having the insert composed of the hard and soft metals or materials, the insert can better withstand wear under different conditions. On some surfaces, the hard piece or

portion 14 may resist wear better than the piece or portion 15, whereas on other surfaces the portion 15 may better resist wear, so that the two materials assist one another in resisting wear under different conditions. The insert may be at different positions so as to be disposed at the point where the rundown of the heel usually occurs.

The insert 13 has a flange 18 embedded in the rubber, whereby to anchor the insert in place, to prevent same from being loosened or lost.

The nail holes 17 are disposed adjacent to the margin of the heel, for securing the heel to the shoe or other article of foot wear, and those nail holes 17 at the opposite sides are located in those arms of the grooves 9 adjacent to said sides of the heel.

There are three grooves 9 in the tread of the heel as shown, but the number of grooves may vary with heels of different sizes. For example, small heels, such as used on ladies' shoes, may have only one or two grooves.

Having thus described the invention, what is claimed as new is:—

1. A heel, and an insert in the heel at the point where the most wear occurs and composed of pieces of relatively hard and soft metals.

2. A heel, and an insert in the heel at the point where the most wear occurs and composed of pieces of relatively hard and soft metals secured together, with the hard piece disposed toward the margin of the heel.

In testimony whereof I hereunto affix my signature.

LOUIS KAPLAN.
